Primary Examiner — Natasha Vujcic*Assistant Examiner* — Kyle A. Edelmaier(74) *Attorney, Agent, or Firm* — Jose Cherson Weissbrot(57) **CLAIM**

The ornamental design for a dehumidifier with LED light as shown and described.

DESCRIPTION

FIG. 1 is a perspective view of a dehumidifier with LED light, showing my new design;

FIG. 2 is the second perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 2; and,

FIG. 12 is a partial enlarged view of FIG. 2.

The broken lines in the figures are for the purposes of illustrating portions of the dehumidifier with LED light, which form no part of the claimed design. The broken lines in FIGS. 1, 2, 9, 10, 11, and 12 depict the boundaries of the detail enlargement views that form no part of the claimed design.

1 Claim, 10 Drawing Sheets(56)
